(57) **CLAIM**

The ornamental design for an intrauterine insertion device, as shown and described.

DESCRIPTION

FIG. 1 is a perspective view of an intrauterine insertion device;

FIG. 2 is a front view of an intrauterine insertion device;

FIG. 3 is a back view of an intrauterine insertion device;

FIG. 4 is a left side view of an intrauterine insertion device;

FIG. 5 is a right side view of an intrauterine insertion device;

FIG. 6 is a top view of an intrauterine insertion device; and,

FIG. 7 is a bottom view of an intrauterine insertion device.
